14 Claims. (Cl. 274—21)

This invention relates generally to phonographs, and more particularly to dictating machines.

It is an object of this invention to facilitate the operation and improve the performance of dictating machines by providing means for controlling the position of the stylus relative to the carriage under certain operating conditions.

Other objects and advantages of this invention will appear hereinafter.

This application is a division of the United States application for Letters Patent Serial No. 731,795, filed August 13, 1924, for which Letters Patent 1,759,654, dated May 20, 1930, was granted.

A preferred embodiment of the invention selected for purposes of illustration is disclosed in the accompanying drawing, in which—

Fig. 1 is a perspective view of the carriage of a transcribing machine having this invention applied thereto.

Fig. 2 is a detail perspective view to slightly reduced scale of certain of the parts shown in Fig. 1.

Fig. 3 is a side elevation to reduced scale and partly in section, of the carriage shown in Fig. 1, showing additional parts of the dictating machine.

Fig. 4 is a sectional view on the line 4—4 of Fig. 3, with parts broken away to more clearly disclose the construction.

Referring first to Fig. 3 of the drawing, mounted near the right front corner of the base plate, (not shown) of a dictating machine of the transcribing type, is an upwardly projecting standard 4, only the upper portion of which is shown. A similar standard, (not shown) is mounted near the left front corner of the said base plate, and these two standards support near their upper ends a guide rod 2 which extends along the front of the machine. These two standards are provided below the guide rod 2 with suitable aligned bearings for rotatably supporting a feed screw 3 which extends parallel to the guide rod 2.

Near the rear corners of the aforementioned base plate two other standards 4, only one of which is shown, support a second guide rod 5 which extends parallel to the first guide rod.

The base plate is also provided with suitable means, (not shown) for supporting a rotatable mandrel 7, which is adapted to carry a cylindrical phonograph record 8. The mandrel 7 and the feed screw 3 are arranged to be rotated by

suitable driving means, (not shown) such as an electric motor.

Slidably mounted on the guide rod 2 is a carriage 6, which has a downwardly and rearwardly projecting arm which underlies the mandrel 7 and record 8, and which slidably engages the other guide rod 5. The carriage 6 is adapted to be moved along the guide rods and the record supported on the mandrel 7 by means of the feed screw 3. The feed screw 3 normally is engaged by a feed nut 9 on one end of a lever 10 which is fixed on a pivot member 11 rotatably supported by the carriage 6. Fig. 3 shows the lever 10 and its pivot member 11 turned in a counter-clockwise direction to disengage the feed nut 9 from the feed screw 3.

Referring to Figs. 1 and 3, the upper portion or head of the carriage 6 supports a sound box 12 for reproducing sound recorded on the record 8. The sound box 12 comprises a diaphragm 13, which is connected by a wire 14 to one end of a lever 15. The other end of the lever 15 carries a stylus 16 for engaging the record 8 carried by the mandrel 7.

For the purpose of allowing the stylus to move toward and away from the mandrel 7, to accommodate for records of different thicknesses and for irregularities in the record surface, the stylus lever 15 is pivotally mounted intermediate its ends upon the fork 17 carried by one arm of a bell crank lever 18. The wire 14 connecting the diaphragm and the stylus lever passes through an opening in the bell crank 18. The bell crank 18 is pivotally mounted at 19 on a horizontal pivot carried by the member 20.

The arm of the bell crank 18 which carries the stylus lever 15 has at its upper end a pin 22 which engages an opening in a stirrup member 23 carried by the sound box 12. This arrangement permits a limited movement of the bell crank end relative to the carriage 6 toward and away from the record surface and to the left and right relative to the record grooves. This arm of the bell crank normally is moved downwardly by gravity to maintain the stylus in contact with the grooves of the record 8, regardless of the outside diameter of the record. To insure this contact between the stylus and the record the bell crank may be connected by means of a tension spring 21 to a downwardly projecting ear of the member 20 so

as to bias the bell crank about its pivot 19 in a counter-clockwise direction. This flexible stylus mounting permits the stylus to move in a direction toward and from the record surface within the limits imposed by members 22 and 23, where-

by the stylus may follow any irregularities in the record without interrupting the connection between the stylus and the diaphragm 13.

In addition to the above-described function, the 5 horizontal pivot 19 of the bell-crank 18 permits the arm of the bell crank carrying the stylus lever to be raised from record engaging position. Ordinarily, it is preferred not to lift the stylus and again drop it on the record surface, because this 10 operation pits the surface of the record, and these pits will cause undesirable noises during a subsequent reproduction of the speech on the record. For this reason, it is the usual practice to leave the stylus in contact with the record surface during 15 backspacing movements, the freedom of movement of the stylus toward and from the record surface permitting it to ride over the ridges between the grooves. However, if the carriage is to be moved any great distance along the 20 record, or if a record is to be removed from the mandrel or a new record placed thereon, the stylus should be raised from its record-engaging position.

As may be seen in Figs. 1 and 3, this step may 25 be accomplished by turning the bell crank 18 about its pivot 19 in a clockwise direction. The downwardly projecting arm of the bell crank 18 may be turned in a clockwise direction by the camming action of the rear end of a release lever 30 24 when the latter is turned in a counter-clockwise direction. The release lever 24 is mounted on the carriage 6 so as to turn about the axis of the guide rod 2, and preferably this lever will be arranged so that the operator may conveniently 35 turn the lever 24 in a counter-clockwise direction by raising its forwardly projecting end.

When the release lever 24 is rocked in a counter-clockwise direction the rear end of this 40 lever also engages the upwardly projecting rear end of the feed nut lever 10. This action rocks the latter lever in a counter-clockwise direction to disengage the feed nut 9 from the feed screw 3. Thus it is seen that by lifting the forward end 45 of the lever 24, the stylus is raised from the record surface, and the feed unit is lifted from the feed screw, and the carriage 6 is free to move along its guide rods 2 and 5. For a more complete description of the action of the release lever 24 reference should be made to Patent No. 1,759,654 50 of which this application is a division, as set forth hereinbefore.

Referring to Figs. 2 and 3, the member 20 is provided with a pin 25 extending substantially at right angles to the pivot 19. The pivot pin 25 is supported in the casing of the sound box 12. The pivot pin 25 permits turning movement of the member 20 relative to the carriage and across the record grooves, and consequently provides for movement of the stylus 15 across the grooves. 60 This freedom of movement of the stylus is limited by the engagement of the pin 22 and the stirrup member 23.

It is seen that the stylus for reproducing speech recorded on a record is mounted so as to have 65 limited movement across the record grooves as well as limited movement toward and from the record surface, both movements being relative to the movable carriage and the record mandrel. This freedom of movement permits accurate 70 tracking of the stylus in the record groove when the carriage is moving along the revolving record under normal operating conditions.

It is frequently necessary to move the carriage 75 backward to repeat a portion of the recorded dictation, and backspacing means are usually

provided for this purpose. Such backspacing movement preferably is effected by sliding the stylus back over the record without lifting the stylus from the record surface. The stylus should be free to move toward and from the record surface during such backward movement of the carriage so that the stylus can ride over the ridges between the record grooves.

However, it has been found that if freedom of movement of the stylus across the record 10 grooves relative to the carriage is also permitted during the backspacing movement, the stylus will not be backspaced the same distance as the carriage. The frictional resistance to movement of the stylus out of one groove and into the next 15 groove is greater than the frictional resistance to the turning of the member 20 about its pivot pin 25. As a result, the stylus may not be moved backwardly at all until the carriage has moved sufficiently to cause the side wall of the stirrup 23 20 to engage the pin 22 on the end of the bell crank 18.

In most instances the operator wishes to backspace the stylus only a short distance, perhaps to 25 pick up the last word or two after an interruption, or to make certain that a word was correctly understood. If the carriage is backspaced only a small distance, the stylus may not be moved at all relative to the record. This is particularly true if the stylus has lagged behind its normal position relative to the carriage during the forward movement of the carriage. Consequently, it may be necessary for the operator to backspace the carriage a relatively great distance in order to move the stylus back to repeat only a few words. 30

This operation requires repeated actuation of the backspacing mechanism, either manually or by known power-operated means, and may involve a considerable loss of time. In most cases, upon 35 the completion of the backspacing movement the stylus is left at or near one end of its range of movement relative to the stirrup, thereby impeding free tracking of the stylus when the carriage again moves forward.

To overcome these objectionable features this 40 invention provides means for preventing relative movement across the record grooves between the stylus and the carriage during back-spacing movement.

Referring to Fig. 3, the carriage 6 may be 45 backspaced along the record by depression of the forwardly projecting end of a lever 26. This lever 26 is integrally connected to a collar 29 which is pivotally mounted on an extending cylindrical portion of the carriage 6 which surrounds the guide rod 2. Thus it is seen that the lever 26 turns about the axis of the guide rod 2.

Lever 26 carries on its upper portion a pawl 27. The pawl 27 is pivotally mounted on the lever 26, and preferably is provided with yielding means, 50 (not shown) normally to maintain the pawl in a forwardly projecting position. For a further disclosure of the backspacing mechanism, reference may be had to United States Letters Patent No. 1,030,740 to T. H. Macdonald, June 25, 1912. 55

When the forward end of the lever 26 is depressed by the operator, this lever turns in a clockwise direction to bring the pawl 27 into engagement with a rack 28 carried by the standards 1 and extending longitudinally of the machine 70 near the guide rod 2. The pawl 27 engages the teeth of the rack 28, and upon further turning of the lever 26 by the operator, the pawl is turned about its pivot to move the carriage a short distance back along the guide rod 2.

Referring to Fig. 1, the collar 29 is provided with a notch 31 which engages an arm 30 fixed on the end of the pivot member 11. As the lever 26 is turned to backspace the carriage, the notch 31 turns the arm 30 and its pivot member 11 in a counter-clockwise direction. This turning of the pivot member 11 also turns the lever 10 which is fixed to the member 11, to disengage the feed nut 9 from the feed screw 3 before the pawl 27

16 engages the rack 28 to move the carriage 6 backwardly along the guide rod 2.

As may be seen in Figs. 1 and 3, the rear end of the lever 10, when turned in a counter-clockwise direction, is adapted to engage a spring member 32 carried on one end of a lever 33 prior to the actual backspacing movement of the carriage 6. The lever 33 is pivotally mounted intermediate its ends on the carriage 6 at 34, and engagement of the rear end of the lever 10 and the spring member 32 cams the lever 33 in a clockwise direction. The other end 35 of the lever 33 is bent so as to lie substantially parallel and adjacent to the diaphragm 13.

As the lever 33 is turned in a clockwise direction, the end 35 of the lever is forced upwardly toward the diaphragm 13. This movement causes the end 35 to engage frictionally a curved arm 36 integrally connected to the member 20. The frictional engagement of 35 with the curved arm 36 is effective to prevent any turning of the member 20 about its pivot pin 25. Thus it is seen that movement of the stylus relative to the carriage is prevented during backward movement of the carriage.

35 The arrangement described operates to fix the position of the stylus relative to the carriage prior to backspacing movement regardless of the relative positions of the stylus and carriage, and consequently the stylus will always be moved 40 backwardly the same distance as the carriage.

It will be understood that the invention may be variously modified and embodied within the scope of the subjoined claims.

We claim:

45 1. In a dictating machine, a carriage; a stylus mounted on the carriage and having tracking freedom of movement relative to the carriage and along a grooved record-surface; means for backspacing the carriage; and means for causing the stylus to be backspaced an amount equal to the backspacing movement of the carriage, irrespective of its position with respect to the carriage before the backspacing operation has been started.

50 55 2. In a phonograph, the combination of a support for a record, sound reproducing means comprising a stylus mounted for movement to track the grooved surface of a record carried on the record support; means for shifting the stylus back toward the beginning of the record by causing the same to skid or glide over the surface of the record; and means for causing the stylus to occupy, upon the completion of the backspacing movement, substantially the same position relative to the sound reproducing means which it occupied before the back-spacing movement was started.

3. In combination, a carriage, a stylus carrier on the carriage capable of being selectively supported in a raised or a lowered position and mounted for lateral movement with respect to the carriage when in said lowered position, and means effective for locking said carrier in any occupied position within the range of its said lateral movement.

4. In combination, a carriage, a stylus carrier on the carriage capable of being selectively supported in a raised or a lowered position and mounted for lateral movement with respect to the carriage when in said lowered position, and means comprising a manually operable part effective for locking said carrier in any occupied position within the range of its said lateral movement.

5. In combination, a carriage movable in a rectilinear path, a stylus carrier support mounted on the carriage for pivotal movement in a plane parallel to the path of travel of said carriage, and controllable means for holding said support in any occupied position within its range of pivotal movement.

6. In combination, a carriage, a stylus carrier support mounted on the carriage for pivotal movement in a plane in which said stylus is capable of functioning, a lever mounted on the carriage and capable of engaging the support in any of its positions within said plane to hold the support in any such position against such pivotal movement, and means to control the operation of said lever.

7. In combination, a carriage, a stylus carrier support mounted on the carriage for pivotal movement in a plane in which said stylus is capable of functioning, a lever mounted on the carriage and capable of engaging the support in any of its positions within said plane to hold the support in any such position against such pivotal movement, and resiliently co-operating means for causing the lever to be operative.

8. In combination, a carriage; a stylus-carrier support pivotally mounted on said carriage; a feed nut mounted on the carriage; a backspace device mounted on the carriage; means operated by the backspace device for moving the feed nut to inoperative position; an operable lever for holding the stylus-carrier support against pivotal movement; and a spring tensioned by the movement of the feed nut to inoperative position for resiliently operating said lever into holding relationship with said stylus-carrier support.

9. In combination, a frame; a record-support; a sound-box carriage mounted on the frame for to and fro movement; a sound-box; a sound-box stylus mounted for tracking movement relative to the record; means for backspacing the sound-box carriage while the stylus remains in engagement with the record-surface; and means operated as an incident to the operation of the backspacing means for positively holding said stylus in any occupied position during backspacing movement of the carriage.

10. In combination, a frame; a record-support; a sound-box carriage mounted for to and fro movement; a sound-box; a sound-box stylus mounted for tracking movement relative to the record; means for backspacing the carriage step-by-step a predetermined extent at each step while the stylus remains in engagement with the record-surface; and means operated as an incident to the operation of the back-spacing means for positively holding said stylus in any occupied position during backspacing movement of the carriage whereby said stylus is constrained to move a distance each time said carriage is stepped back equal to the said extent of movement of said carriage.

11. The combination in a device of the character described, of a sound-box, a stylus, a stylus carrier support pivotally mounted on the sound-box so as to have a limited range of lateral move-

ment relative to said sound-box in a plane in which said stylus is capable of functioning, and means for locking said support against such movement relative to the sound-box at any point within its limited range in said plane.

5 12. In a dictating machine, a carriage, a stylus mounted on the carriage and having tracking freedom of movement relative to the carriage and along a grooved record-surface, means for back-spacing the carriage, and means operatively associated with the backspacing means for causing the stylus to be always backspaced an amount equal to the back-spacing movement of the carriage.

10 13. In combination, a carriage, a stylus, a stylus carrier mounted for lateral movement on the carriage in a plane in which said stylus is capable of functioning, and means for locking said

carrier in any occupied position in said plane against lateral movement relative to the carriage.

14. In a phonograph, the combination of a support for a record, sound-reproducing means comprising a stylus mounted for a range of free movement relative to the sound-reproducing means in which to track a record; means for shifting said stylus upon the record by causing the same to skid or glide over the surface of the record; and means operated by the means for shifting the stylus for causing the stylus to occupy upon completion of the shifting movement substantially the same position within its range of free movement, that it occupied before the shifting movement was started.

JOSEPH M. LUCARELLE.
JOHN E. RENHOLDT.
